UNITED STATES PATENT OFFICE.

JOSEPH F. MACKOVITCH, OF CONWAY, PENNSYLVANIA, ASSIGNOR OF ONE-THIRD TO
MANDALINE MAILING, OF PITTSBURGH, PENNSYLVANIA.

BURGLAR ALARM.

1,421,972.

Specification of Letters Patent.

Patented July 4, 1922.

Application filed December 17, 1921. Serial No. 523,047.

To all whom it may concern:

Be it known that I, JOSEPH F. MACKOVITCH, a citizen of Jugo-Slavia, residing at Conway, in the county of Beaver and State 5 of Pennsylvania, have invented certain new and useful Improvements in Burglar Alarms, of which the following is a specification.

This invention relates to certain new and 10 useful improvements in burglar alarms of that type embodying audible means for warning a person of the attempt of a person to effect a clandestine entrance to his home.

The primary object of the invention is to 15 provide means of a spring motor driven type for effecting the successful firing of cartridges upon an unauthorized attempt to open a door or the like.

Another object of the invention is to 20 provide means for releasing a motor actuated alarm of a novel construction whereby the same may be released by an authorized person before opening a door or window though inaccessible to an unauthorized person.

Still another object of the invention is to 25 generally simplify and improve devices of the above kind.

With the above general objects in view 30 and others that will appear as the nature of the invention is better understood, the same consists of the novel form, combination and arrangement of parts hereinafter more fully described, shown in the accompanying drawings and claimed.

In the drawings, wherein like reference 35 characters designate corresponding parts throughout the several views,

Figure 1 is a fragmentary elevational view showing a sliding door and frame 40 equipped with a burglar alarm in accordance with the present invention,

Figure 2 is a transverse vertical sectional view of the alarm mechanism per se drawn on a larger scale,

Figure 3 is a longitudinal vertical sectional view of the device shown in Fig. 2,

Figure 4 is a fragmentary sectional view taken substantially upon line IV-IV of Fig. 3,

Figure 5 is a vertical sectional view taken substantially upon line V-V of Fig. 3 with parts omitted,

Figure 6 is a horizontal sectional view taken substantially upon line VI-VI of Fig. 1 and showing the alarm release device 55 partly in top plan and partly in horizontal section,

Figure 7 is an elevational view of the alarm release device, and

Figure 8 is a perspective view of the releasing cam for the swinging member of the alarm release device.

Referring more in detail to the several views, the alarm mechanism of the present invention preferably embodies a rectangular casing 5 adapted to be secured at any convenient or preferred point such as upon the frame 6 of a sliding door 7 as shown in Fig. 1, said casing 5 having a spring motor 8 suitably mounted therein including a 70 housed coil spring adapted to drive a transverse power shaft 9 having spur gears 10 and 11 fixed thereon. A suitable vertical bearing 12 is secured to one side wall of the casing 5 and has a short winding shaft 13 75 journaled therein, said shaft 13 being provided with a squared lower end 14 terminating within the casing in line with an opening 15 in the bottom wall of the casing through which a winding key 16 may be inserted for engagement with the end 14. A gear wheel 17 is secured upon the upper end of the shaft 13 in mesh with the gear 10 so that the spring of the motor 8 may be wound upon rotating the key 16 in the 85 proper direction, unwinding of said spring being prevented in any usual or preferred manner as by means of a ratchet mechanism diagrammatically shown and illustrated at 18. 90

Another transverse shaft 19 is journaled in the casing above the shaft 9 and has a bevel gear 20 and a spur gear 21 secured upon one end thereof with the spur gear 21 meshing with the gear 11. An upper corner 95 of the casing is divided by suitable partitions into a firing chamber 22 having a revolver cylinder 23 suitably journaled therein, and one of said partitions has a hammer 24 hinged thereto so that its firing pin 25 100 is in proper position to engage the priming cap of the adjacent bullet or cartridge of the cylinder 23, said hammer 24 being normally projected toward the cylinder by

means of a relatively strong spring 26. The hammer 24 is provided with an arm 27 which extends downwardly below the pivot of the hammer and inwardly to the interior 5 of the chamber 22 where it has its lower end pivotally attached to the lower end of a push rod 28 which is suitably guided for vertical movement in the chamber 22 at the inner side of the cylinder 23. The rod 28 10 is provided with a spring pressed pawl 29 disposed to engage the ratchet teeth 30 provided in the usual way upon a cylindrical projection rigid with the central portion of the inner face of the cylinder 23.

15 As shown in Fig. 2 the gearing 21 is provided with one or more laterally projecting pins 31 while the upper end of the hammer 24 is provided with a lateral angular pin 32 arranged in the path of said pins 31 so 20 that upon rotation of the gear 21 in the proper direction the hammer is caused to be swung away from the cylinder and then released so as to cause the firing pin 25 to strike the priming cap of the cartridge under the action of the spring 26.

25 The motor 8 may be operatively geared by means of a spur pinion 33 to another transverse shaft 34 which carries the pinion 33 and an escapement wheel 35, for sounding 30 an alarm through the action of the escapement lever 36 and pivoted hammer 37 which is connected to the escapement lever by means of a link 38 and which is extended through the adjacent wall of the casing 5 in 35 a position to strike a suitable sound producing shell 39. The shafts upon which the escapement lever 36 and hammer 37 are respectively pivoted are indicated at 40 and 41 and may be secured at one end to the adjacent side wall of the casing and supported 40 near the other end by a bracket 42.

45 A shaft 43 is suitably journaled longitudinally of the casing in a bracket 44 above the motor 8 and has a bevel pinion 45 fixed upon its inner end normally meshing with the bevel gear 20. As shown in Fig. 4 the shaft 43 is hollow and rotatably and slidably mounted upon a stationary spindle 46 which has its outer end fastened as at 47 50 in the end wall of the casing 5 opposite that adjacent which the chamber 22 is formed, a coil compression spring 48 being positioned between the outer end of the shaft 43 and the adjacent wall of the casing so 55 as to normally project the shaft 43 and gear 45 inwardly with the latter meshing with the gear 20. A drum including a separate flange disk 49, a hub 50 and a flange 51 integral with the hub is mounted upon the outer end 60 of the shaft 43 with the flange disk 49 freely revoluble upon the shaft 43 and having transverse openings through which pins 52 65 slidably project, said pins 52 being provided with heads upon their inner ends to limit the inward movement of the disk 49

and being fixed in a circular series to the adjacent wall of the casing concentric with and about the shaft 46. The hub 50 and its flange 51 as well as an adjacent ratchet wheel 53 are fastened to the shaft 43 by 70 means of a key 54 or the like, and a pin 55 extends through and is fixed transversely in the shaft 46 so as to have its opposite ends project through registered and opposite oblique slots in the shaft 43 and hub 50, one 75 of which slots is shown at 56 in Fig. 3. It will thus be seen that when the drum is rotated in one direction the same is caused to move endwise outwardly so as to compress the spring 48 and to cause the shaft 43 and pinion 45 to move therewith so that the pinion 45 is disengaged from the gear 20. This 80 permits the motor 8 to drive the gear 20 and the gear 21 for the actuation of the hammer 24 and the hammer 37. Rotation of the shaft 43 and the gear 45 by means of the gear 20 is normally prevented by means of a pawl 57 engaging the ratchet wheel 53 so that the gear 45 must be released from the gear 20 to permit the device to operate. 85 In order to reset the mechanism the pawl 57 must be manually released and the spring 48 will then immediately return the gear 45 into mesh with the gear 20. Access to the pawl 57 may be had through the hinged cover 58 of the casing. Means is provided for rotating the drum to release the pinion 45 from the gear 20 upon opening of the door 7 and the same includes a flexible cord or cable 59 attached to and partially wound upon the drum in the proper direction, said 90 flexible member 59 passing from the drum outwardly through a side wall of the casing and then downwardly to an alarm release device generally denoted by the numeral 60 95 and clearly shown in Figs. 1 and 6 to 8 inclusive.

100 As shown, the alarm release device comprises a rod 61 slidably mounted in a casing 62 suitably secured to the frame 6 and having its outer end attached to the flexible member 59 while the inner end of the rod 61 is notched as at 63. The rod 61 may be 105 slidably guided by means of screws or the like engaging a longitudinal slot 64 in the 110 rod 61.

115 Another casing 65 is attached to the door 7 and has a catch 66 pivoted thereto as at 67, the free end of the catch 66 being provided with a lateral projection or being of 120 hook shape as at 68 to engage the notch 63 so that when the door 7 is slid open a pull is exerted upon the rod 61 and flexible member 59. The catch 66 may be normally 125 swung inwardly by means of a tension spring 69 for engaging the notch 63 and a double cam disk 70 is pivoted within the casing 65 beneath the catch 66 for releasing the latter. This cam disk may be limited in 130 its rotary movement by means of screws or

the like extending through arcuate slots 71 in the narrow portion of the disk adapted to be engaged by screws or the like fastened to the casing 65 and door 7 and the 5 central portion of the disk 70 is provided with a key hole as at 72 registering with a similar key hole 73 in the door 7 so that a wind key may be inserted to engage the shoulders 74 of the disk 70 so as to rotate 10 the latter for releasing the catch 66 from the outside. Thus, the alarm release device comprises a separable connector, one member of which is attached to the door and the other member of which is attached to the 15 door frame, and one of said members being key actuated for release of the same from the exterior of the dwelling whereby an authorized person may enter the said dwelling without causing the alarm to be placed 20 into operation.

In operation, it will be seen that the catch 66 may be disengaged from the bar 61 by rotation of the cam disk 70 so that an authorized person may enter through the 25 door upon opening the door without exerting a pull upon the bar 61 and flexible member 59. However, should an unauthorized person succeed in unlocking the door 7 with the parts disposed as in Fig. 1 and Figs. 7 30 and 8, so that the door will cause a pull to be exerted upon the bar 61 and flexible member 59 thereby causing a partial rotation of the head and flange 50 and 51 respectively together with the ratchet wheel 53 35 and through the medium of the pin 55 and slots 56, the drum and parts connected therewith will be given an outward endwise movement against the action of the spring 48 so as to release the pinion 45 from the 40 gear 20 and thereby allow the motor 8 to drive the gear 21 which in its rotation, causes successful actuation of the hammer 24 through the medium of the pins 31 and 32. At each rocking movement of the hammer 45 45 the rod 28 is raised so as to cause the pawl 29 to engage the ratchet teeth 31 and thereby rotate the cylinder 21 for successively bringing a new cartridge into position for engagement by the firing pin 25. At 50 the same time, the hammer 37 is actuated through the escapement mechanism for sounding the bell 39.

The chamber 22 may be provided with a metallic shell 75 to prevent flames from 55 passing outwardly of the casing while providing a passage for the report or sound as each bullet is fired, but as the specific construction of the same is not a part of the present invention, it is only shown in a 60 general way.

From the foregoing description it is believed that the construction and operation as well as the advantages of the present invention will be readily understood and 65 appreciated by those skilled in the art.

Minor changes may be made without departing from the spirit and scope of the invention as claimed.

What is claimed as new is:—

1. In a burglar alarm of the class described, a rotatable cartridge holding cylinder, a pivoted hammer having a firing pin for impacting the priming caps of the cartridges in said cylinder, means operable upon the swinging of said hammer for rotating the cylinder step by step for bringing successive cartridges in the path of said firing pin, a rotatable member disposed adjacent the hammer and having lateral pins projecting from one face thereof toward the hammer, a motor to rotate said rotatable member, a pin fixed to and extending from the upper end of the handle in the path of said first named pins for retracting the hammer from the cylinder, and 75 automatically releasing the same as the rotatable member is rotated, means to control the operation of said motor, and a spring normally urging the hammer toward the cylinder. 80

2. In a burglar alarm of the class described, a sound producing means including a rotatable gear and a spring motor operatively geared thereto, a stationary spindle, a rotatable shaft journaled upon said spindle and having a pinion fixed upon one end thereof, yieldable means for normally causing endwise movement of said shaft and pinion to engage the latter with the gear, means associated with said shaft for preventing rotation of the same in one direction as influenced by said motor, and means operable upon rotation of the shaft in the opposite direction for causing endwise movement of the same together with its pinions 100 against the action of said yieldable means so as to release the pinion from the gear and permit rotation of the gear by means of said motor. 105

3. In a burglar alarm of the class described, a sound producing means including a rotatable gear and a spring motor operatively geared thereto, a stationary spindle, a rotatable shaft journaled upon said spindle and having a pinion fixed upon one end 110 thereof, yieldable means for normally causing endwise movement of said shaft and pinion to engage the latter with the gear, means associated with said shaft for preventing rotation of the same in one direction 115 as influenced by said motor, means operable upon rotation of the shaft in the opposite direction for causing endwise movement of the same together with its pinions against the action of said yieldable means so as to release the pinion from the gear and permit rotation of the gear by means of said motor, said last named means including an oblique slot in said shaft, and a fixed radial pin engaging said slot. 120 125

4. An alarm mechanism of the class described comprising a spring motor, a gear driven thereby, a pivot hammer having a firing pin, a spring for urging the hammer to firing position, means including cooperating pins upon the hammer and gear for intermittently swinging the hammer from firing position as the gear is rotated, a second gear rotatable with the first named gear, a stationary spindle, a hollow shaft journaled upon and slidable longitudinally on said spindle, a pinion fixed upon one end of the hollow shaft, a spring normally urging the hollow shaft in one direction to engage the pinion with said second named gear, means to cause endwise movement of the hollow shaft upon rotation of the same in one direction to disengage the pinion from the second named gear, and ratchet means for preventing rotation of the hollow shaft in the opposite direction to which it is urged by said motor.

5. An alarm mechanism of the class described comprising a spring motor, a gear driven thereby, a pivot hammer having a firing pin, a spring for urging the hammer to firing position, means including cooperating pins upon the hammer and gear for intermittently swinging the hammer from firing position as the gear is rotated, a second gear rotatable with the first named gear, a stationary spindle, a hollow shaft journaled upon and slidable longitudinally on said spindle, a pinion fixed upon one end of the hollow shaft, a spring normally urging the hollow shaft in one direction to engage the pinion with said second named gear, means to cause endwise movement of the hollow shaft upon rotation of the same in one direction to disengage the pinion from the second named gear, and ratchet means for preventing rotation of the hollow shaft in the opposite direction to which it is urged by said motor, means to rotate said hollow shaft including a flexible member, means for causing endwise movement of the hollow shaft including a drum to which the flexible member is attached and which is provided with

an oblique elongated slot, said drum being fixed upon the hollow shaft, and a radial pin 50 being fixed upon the spindle and projecting into said slot.

6. As an actuating means for an alarm release pull cord, a separable connector for attachment to a slidable closure and its frame and including a slidable bar having a guiding means adapted to be attached to said frame and to the pull cord, said bar having a notch in its inner end, a pivot member having a hooked end yieldingly engaged in said notch and having a casing adapted to be secured to the slidable closure, and key operated means operable from the outside of the closure for swinging the pivoted member so as to disengage its hooked end from said notch. 60

7. As an actuating means for an alarm release pull cord, a separable connector for attachment to a slidable closure and its frame and including a slidable bar having a guiding means adapted to be attached to said frame and to the pull cord, said bar having a notch in its inner end, a pivot member having a hooked end yieldingly engaged in said notch and having a casing adapted to be secured to the slidable closure, and key operated means operable from the outside of the closure for swinging the pivoted member so as to disengage its hooked end from said notch, said last named means including a rotatable disk having a pair of opposite cam devices upon one side thereof and arranged within the casing between the pivoted member and its casing. 70

8. As a means for actuating the pull cord of an alarm release mechanism, a separable connector including a pair of members respectively adapted for attachment to a slid- 85 able closure and its frame interiorly of a dwelling, said members being constructed for interlocking engagement, yieldable means 90 to normally hold said members interlocked, and key operated means operable from the exterior of the dwelling for disconnecting said members.

In testimony whereof I affix my signature. 95
JOSEPH F. MACKOVITCH.
